United States Patent

Des. 237,497
Patented Nov. 4, 1975

237,497

DEODORIZER

Theodore C. Andreopoulos and Edgar R. Bourke, II, Way-
land, Mass., assignors to Bath-Air Systems, Inc.

Filed June 17, 1974, Ser. No. 479,819

Term of patent 14 years

Int. Cl. D23—04

U.S. Cl. D23—150

FIG. 1

FIG. 3

FIG. 2

FIG. 4

FIG. 5

FIG. 6

FIG. 1 is a perspective view of a deodorizer showing our new design;

FIG. 2 is a side elevational view of the deodorizer,
FIG. 3 is a front elevational view of the deodorizer,
FIG. 4 is a rear elevational view of the deodorizer,
FIG. 5 is a top view of the deodorizer, and
FIG. 6 is a bottom view of the deodorizer.

The electrical cord and plug shown in FIG. 1 is in broken lines for illustrative purposes only.

We claim:

The ornamental design for a deodorizer, as shown.
